Filed Apr. 12, 1967, Ser. No. 6,650

Term of patent 14 years

(Cl. D54—12)

FIG.1

FIG.2

FIG.3

FIG.4

FIG.5

FIG. 1 is a front view of a spoon or similar article showing my new design.

FIG. 2 is a rear view thereof.

FIG. 3 is a side view thereof, the undisclosed side being substantially identical with the side shown in FIG. 3.

FIG. 4 is an enlarged sectional view taken on line 4-4 of FIG. 1.

FIG. 5 is an enlarged sectional view taken on line 5-5 of FIG. 1.

FIG. 6 is a front view thereof on a further enlarged scale showing in detail a portion of the handle.

The essential feature of my design for a spoon or similar article resides in a handle with a die-struck half ring surface ornamentation in combination with a handle configuration as shown.

I claim:

The ornamental design for a spoon or similar article, substantially as shown and described.
